(57) **CLAIM**

The ornamental design for a display screen with graphical user interface including a sustainability dashboard for an enterprise, as shown and described.

DESCRIPTION

FIG. 1 depicts a first embodiment of a display screen with graphical user interface including a sustainability dashboard for an enterprise; and,

FIG. 2 depicts a second embodiment of the display screen with graphical user interface including a sustainability dashboard for an enterprise.

The broken lines showing a display screen and portions of the graphical user interface illustrate portions of the article and form no part of the claimed design.

ENERGY METRICS FROM TIME OF IPM+ INSTALLATION ON SEPTEMBER 25, 2014

If we were to assume that the energy consumed prior to IPM+ Installation on September 25, 2014 was at 100%, below is the relative energy saving.

40%

ENERGY SAVED
2.80Gwh

ENERGY CONSUMED
4.99Gwh

CO₂ EMISSION SAVED
135.0Kg

WATER SAVED
27.57KI

TREES SAVED
20

WATER SAVED
2,902.6INR

COMPARATIVE ENERGY TEND

Pre IPM+ Installation Post IPM+ Installation

ENERGY METER

Peak Energy* Consumption
37.37Kwh
November 14, 2014

*Peak Energy is the highest total amount of energy consumed on a given day by all connected nodes.

Avg. Energy Consumption/Node per Day
0.59Kwh

FIG. 2
